(57) **CLAIM**

The ornamental design for a ceiling fan package, as shown and described.

DESCRIPTION

FIG. 1 is a front, bottom perspective view of a ceiling fan package, showing my new design;

FIG. 2 is a rear, top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a perspective view of the ceiling fan package, shown in a position of use with an exemplary ceiling fan; and,

FIG. 10 is another perspective view thereof, shown with the exemplary ceiling fan placed in the ceiling fan package. The broken lines in FIGS. 1 and 3 depict portions of the ceiling fan package that form no part of the claimed design. The remaining broken lines in the form of ceiling fan components in FIGS. 9-10 depict environmental subject matter and form no part of the claimed design.

1 Claim, 10 Drawing Sheets
